UNITED STATES PATENT OFFICE.

GEORGE F. WELLS, OF SAN FRANCISCO, CALIFORNIA.

ORCHESTRION.

SPECIFICATION forming part of Letters Patent No. 387,128, dated July 31, 1888.

Application filed March 18, 1886. Serial No. 195,687. (No model.)

To all whom it may concern:

Be it known that I, GEORGE F. WELLS, a citizen of the United States, residing in the city and county of San Francisco and State of California, have invented a new and useful 5 Automatic Musical Instrument, of which the following is a specification.

My invention relates to that class of musical instruments known as "reed instruments," where perforated music rolls or sheets are passed over a range of holes connecting with the notes. It will be understood by reference to the accompanying drawings and the letters referring thereto.

15 Figure 1 is a perspective view of an orchestrion with my improvement attached. Fig. 2 is a rear view of the same with the back and sounding-board removed for the purpose of showing the operating mechanism. Fig. 3 is 20 an edge view of a portion of the same mechanism as that shown in Fig. 2. Fig. 4 is a broken perspective elevation showing the keyboard and the lever which operates the modification of the volume of the tones. Fig. 5 is a 25 longitudinal section showing the keys and their connection with the swells and regulator for the volume of sound. Fig. 6 is a perspective view showing the general construction. Fig. 7 is a rear view of the bellows-operating 30 mechanism. Fig. 8 is a broken sectional view of the same. Fig. 9 is a front view of the indicator. Fig. 10 is a broken perspective view.

The object of my invention is to afford the 35 means of operating the automatic reed-instrument with all the effect of the hand-instrument, allowing any required variation of time and expression by the performer, still leaving the instrument free to play automatically, as will be fully explained.

40 A represents the frame or body of the instrument; B, the weight which operates the mechanism; C, the weight-cord; D, the weight-cord sheaves; E, the weight-cord winding-drum; F, the main driving-wheel; G, the 45 ratchet-wheel and pawl; H, the pinion which gears with the wheel F and drives the wheel I, which gears with the pinion J, giving motion to the shaft J' and the wheel K, which carries the tappet-pins L L L L to operate upon the 50 lever R, which connects with the spring-lever S by the weight and cord T.

M represents the driving sheave, over which the cord passes to the sheave N, which operates the sheave O by means of the sheave N', operating the music-rolls O² and P, which pass 55 the perforated music-paper over the range T² in the usual manner well known to that class of instruments.

The keys are lettered A' B' Z C' D' E' F' G' Y X W I² J² F² H². 60

I² is the lever by which the front swell is operated. The lever B² is connected with the key J² for the purpose of operating the swell or sound-opening R² by closing the valve G². The lever D², being pressed down, operates 65 the lever E² and raises the swell A² by means of the pin E². The time-indicator K² has the thumb-knob L² and the pointer N². It has also the words "Largo," "Andante," "Allegro," and "Presto," referring to the different time 70 to which the pointer is to be set to give the required time.

I have shown in Figs. 7 and 8 the mode of attachment for operating the pedals or levers O' and P', which connect with and operate the bellows Q' by means of the cords T' and T² over the sheaves R'. The spring S' throws the bellows together, causing it to blow as soon as the same is released. The walking-beam or lever N', fulcrumed at N⁵, 75 so being operated by the cam H' and connecting-rod K' and spring V², and connecting by means of the rods L' and M', operates the bellows Q'.

In Fig. 3, V and V represent miter-gear, 85 which is operated by the crank U for the purpose of revolving the drum E and winding the cord C and raising the weight B.

The following is the operation of my improved instrument: The crank U, being revolved, winds the cord C over the drum E, thus raising the weight B. The gravity of the weight B is sufficient to revolve the wheel F, giving motion to the pinion H, which is upon the same shaft with and revolves the wheel I, 90 which gears with and revolves the pinion J, which is upon the same shaft with and gives motion to the wheel K and sheave M. The wheel K carries the tappet-pins L, which as the wheel K is revolved strike the governor-lever R. The sheave M is connected with the sheave N by the belt or cord shown, thus giving 95 100

ing motion to the rolls O³ and P, which carry the perforated music-sheet over the range T², to be operated as all other musical instruments of this class operate.

5 The object of the tappet-pins L is to check the velocity of the wheel K, thus checking the motion of the rolls, (and consequently the time of the music.) The lever R is connected with the friction spring-lever S by the cord c which suspends the weight T. The key X is connected with the lever S by means of the cord X', and when it is depressed it raises the lever S up toward the periphery of the wheel K, slackening the cord which suspends the 15 weight T, and as the tappets L strike the lever R the ball T jerks the lever S up against the periphery of the wheel K with increased force, thereby checking the motion of the same by friction. Thus any variation of the 20 friction applied to the wheel K may be effected by the different degrees of pressure imparted by the operator upon the key X. When released, the lever S is supposed to be so set as to allow a sufficient friction for common 25 time, thus allowing the instrument to play automatically.

The cord O² connects the lever S with the arm M² of the indicator K²; but it is slack except when the machine is to be stopped.

30 When the pointer N² has passed the word "Presto," the cord O² becomes taut and pulls the brake-lever S against the wheel K, thereby stopping the same, and consequently the whole instrument.

35 The lever S² (shown in Figs. 1 and 10) is connected with the lever R by the cord Q², and is operated by the knee when it is desired to allow a more rapid movement by raising the long end of the lever R, and lessening the 40 effect of the tappet-pins L and causing but a slight jerk upon the weight-ball T.

45 For the purpose of operating the bellows automatically, I attach the cam H' upon the shaft J', and as it revolves, the connecting-rod K' is raised by each leaf of the cam H' and returned by the spring V², or any other suitable spring, to produce a regular reciprocating movement, alternately operating the rods L' and M' and the pedals O' and P' and the 50 connecting-cords T' and T³, thus operating the bellows Q'.

The keys A' B' C' D' E' F' G' connect with the lever D². By the lever D² being fulcrumed or hinged at S³, the key A', being 55 nearest the fulcrum, gives the greatest motion to the same, and the motion is gradually less as it reaches the key G', which is farthest from the hinge or fulcrum S³. This lever D² connects with the valve or swell A² by means 60 of the lever E², fulcrumed at E⁴, and the pin E³, and thus as any of the keys from A' to G' are pressed, the valve or swell A² is correspondingly opened, thus increasing the volume of sound.

65 The key J², being operated, operates the lever B², throwing down the valve G² and clos-

ing the valve-opening R², thus lessening the volume of sound. The spring C² returns or opens the valve or door G² when the pressure is removed from the key J². The key I² connects with the lever B³ by means of the joint I⁴ through the lever I³, and operates the valve or door G³, closing the valve-opening R⁴ and lessening the sound from the rear part of the instrument, as shown in the section shown in 70

75 Fig. 5. The following is the operation of the same: The instrument being wound up, raising the weight B, and the music adjusted, it is operated as follows:

80 The pointer N² is removed from the stopping-point on the dial and turned back from the word "Presto," thus releasing the brake by relieving the brake-lever S from the wheel K and allowing the weight B to descend, thus setting the operating mechanism in motion, thereby moving the music-paper over the range T² or holes connecting with the reed. The pointer N² is set upon the dial K² at the point designating the time that is required for the music to be played. This gives a foundation for the time, and will 90

be reliable and exact, being automatically controlled by the action of the governor, as shown; but the time may be varied, accelerated, or retarded as follows: To retard the time, the key X is pressed in a degree corresponding with 95

the effect required, and when it is desired the key X is pressed hard enough to hold the brake-lever S against the wheel K. To accelerate the time, the key W is pressed, pulling the cord W' and drawing the brake lever S 100

back from the wheel K and allowing it to revolve more rapidly. It will be understood that in every instance where the wheel K is revolved, the time is kept uniform by the action of the governor actuated by the contact of the tappets L with the governor-lever R, as has been described. Should it be required to increase the time greatly, the knee 105

is pressed against the knee-stop S² and operates the cord Q² and lever R, which, being fulcrumed at R³, is drawn entirely away from the tappets L and allows the wheel K to revolve rapidly and correspondingly increase the time 110 of the music.

When it is required to execute a soft passage in music, the keys J² and I² and F² and H² are pressed and held during the execution of the entire passage. To produce the "forte," the key A' is pressed, giving the greatest effect upon the front swell, A², as its contact is 115 nearest to the pivot or hinge S³ of the lever D²; but any modification is given by operating the keys B', C', E', F', and G' in their order as they recede from the hinge S³, giving a correspondingly less effect in opening the swell 120 A². The back swell, A³, is opened by pressing the key Z and cord Z'.

The low notes are placed at the back of the instrument, and to give the bass the prominence, the key Z only is operated to open the 125 back swell, A³.

To produce special effect, I press the keys

effecting the high tones or "air" *ff* with the lower notes or accompaniment *pp*. The keys I^1 and F^2 are pressed, closing the valve G^3 , thereby closing or partially closing the opening R^1 , while the front swell is opened to its fullest extent, thus producing the air *ff* and the bass *pp*.

It will be seen that the reverse of the above effect is given by pressing the keys H^1 and J^2 , and at the same time thus closing the valve G^2 , thereby closing the passage R^2 and at the same time pressing the key Z , which fully opens the back swell, A^3 .

By the operation of the above-described combination and arrangement of mechanism and the device shown every effect known to music may be accomplished, and while a novice can operate the instrument with good effect the most talented musician may employ all his musical talent and skill in the production of fine music.

To discharge the air from the bellows at once, the key Y is pressed, opening the door or valve Y^2 by means of the cord Y^1 .

I do not confine myself to any exact form of construction of the parts described, as they may be varied without changing the principle of the invention; but,

Having thus described my invention, what I claim, and desire to secure by Letters Patent, in automatic musical instruments, is—

1. The weight B , the cord C , the sheaves D D , the winding drum E , the wheel F , ratchet-wheel I^1 and pawl G , the pinion H , the wheel I , the pinion J , the wheel K , with tappet-pins L , and the wheel M , in combination with the wheels N , N^1 , and O , for the purpose of operating the music-rolls O^3 and P and carrying the music over the range T^2 , constructed, arranged, and operated substantially as and for the purposes set forth.

2. The wheel K , with tappet-pins L , in combination with the lever R , pivoted at R^3 and

operated in connection with the weight-ball T and friction brake-lever S , for the purpose 45 of regulating and governing or controlling the time of the music, constructed and operated substantially as and for the purposes set forth.

3. The dial-plate K^2 , with the words "Largo," "Andante," "Allegro," and "Pres- 50 to," with indicating-pointer N^2 and lever-arm M^2 , in combination with the levers R and S , and the wheel K , connected by means of the cords O^2 and P^2 , for the purpose of regulating the time of the music and stopping the instru- 55 ment, constructed and operated substantially as and for the purposes set forth.

4. The keys A^1 , B^1 , C^1 , D^1 , E^1 , F^1 , and G^1 , in combination with the front swell, A^2 , connected by means of the levers D^2 and E^2 , pivoted at 60 E^4 , and the pin E^3 , for the purpose of regulating the volume of sound from the higher notes, constructed and operated substantially as and for the purposes set forth.

5. The key J^2 , lever B^2 , and valve G^2 , for the 65 purpose of closing the air-opening R^2 and softening the tone, constructed and operated substantially as and for the purposes set forth.

6. The key I^1 and lever I^3 , jointed at I^4 , the lever B^2 , and valve or door G^3 , for the purpose 70 of suppressing the volume of the low notes, constructed and operated substantially as and for the purposes set forth.

7. The cam H' upon the shaft J' , in combination with the connecting-rod K' , with spring 75 V^2 , the rock-shaft N' , pivoted at N^5 , and the connecting-rods L' and M' , levers O' and P' , and the connecting-cords T' and T^3 , for the purpose of operating the bellows Q' , constructed and operated substantially as and for the pur- 80 poses set forth.

GEORGE F. WELLS.
